6 Claims**ABSTRACT OF THE DISCLOSURE**

This invention is concerned essentially with a small-arms construction including a stock and a barreled action, wherein a bed of resilient material is interposed between the barreled action and stock.

Background of the invention

As is well known to those versed in the art, conventional manufacture of rifles and similar small arms requires the use of a wood stock, being machined, milled or otherwise formed to snugly receive a barreled action. A highly precise fit is essential between the barreled action and stock for best possible accuracy, and this requires tedious and time-consuming effort on the part of highly skilled persons.

It has been proposed to employ rigid, epoxy-type adhesives and Fiberglas materials between the wood stock and metal barreled action for improved fit. However, prior small-arms constructions, both with and without rigid bedding material of epoxy and Fiberglas, or the like, have been found subject to inaccuracy from changes in humidity, temperature and other atmospheric conditions resulting in varying stresses between the barreled action and stock.

Summary

Accordingly, it is an important object of the present invention to provide a unique and highly improved small-arms construction wherein a barreled action is secured to but effectively isolated from a stock of wood, or the like, by means of a resilient bedding material, which produces a greatly improved accuracy under all conditions of use, even including those of rapid fire having substantial shock effects and heating.

It is a further object of the present invention to provide a small-arms construction of the type described wherein dimensional changes of the barreled action and stock are effectively isolated from each other so that stresses are not transmitted therebetween, which results not only in greater accuracy, but enhanced reliability, durability and longer useful life.

It is still a further object of the present invention to provide a small-arms construction having the advantageous characteristics mentioned in the preceding paragraph, which is extremely simple in structure, and effects substantial savings in costs, to enable the small arms to be manufactured and sold at a reasonable price.

Other objects of the present invention will become apparent upon reading the following specification and referring to the accompanying drawings, which form a material part of this disclosure.

Brief description of the drawing

FIGURE 1 is an elevational perspective view showing a rifle or small arms constructed in accordance with the teachings of the present invention.

FIGURE 2 is a partial side elevational view, taken generally along the line 2—2 of FIGURE 1, partly in section, to illustrate internal construction.

FIGURE 3 is a transverse sectional view taken generally along the line 3—3 of FIGURE 2.

2

FIGURE 4 is a partial side elevational view, partly in section, showing a slightly modified embodiment of the present invention.

FIGURE 5 is a transverse sectional view taken generally along the line 5—5 of FIGURE 4.

FIGURE 6 is a transverse sectional view showing another slightly modified embodiment of small-arms construction of the present invention.

Description of the preferred embodiments

Referring now more particularly to the drawing, and specifically to FIGURES 1—3 thereof, an article of small arms or a rifle is shown in FIGURE 1, and there generally designated **10**. The rifle includes a stock **11** and a barreled action **12** associated with the stock.

More specifically, as seen in FIGURE 2, the stock **11** includes an upwardly facing elongate, semi-cylindrical recess or groove **15**, and is further formed with a through opening **16** extending downward from a rearward region of the groove **15** and opening through the underside of the stock **11**. In addition, the stock **11** is formed with one or more, generally vertically extending through openings or holes, including a through opening or hole **17** forward of the opening **16**, and a through hole **18** rearward of the opening **16**. The holes **17** and **18** also pass from lower respective regions of the upwardly facing groove **15** downward and open through the underside of the stock **11**.

The barreled action **12** includes a barrel part **20** generally conformably received in the groove **15**, and an action part **21** secured to a rearward region of the barrel part **20** and depending therefrom through the stock opening **16**. The action part **21** is provided on its underside with a depending trigger **22**, which may be protectively surrounded by a trigger guard **23** secured at its opposite ends to the underside of the action part **21** by a fastener **24**, and to the underside of the stock **11** by a fastener **25**.

The upwardly facing longitudinally extending groove **15** formed in the stock **11** is further formed with a plurality of generally parallel grooves or upwardly facing recesses **28** extending transversely across the groove **15** forward of the hole **17**. Additionally, a transversely extending, upwardly facing groove or recess **29** may be formed in the groove **15** rearward of the stock opening **16**, between the latter and rearward hole **18**. The barreled action **12** may be formed on its underside, say in the barrel part **20**, with a plurality of downwardly facing, generally parallel, transversely extending recesses or grooves **30**, each of which may be located directly over and in facing relation with a respective upwardly facing groove **28**. Similarly, the barreled action **12** may be formed in a rearward region, say in the action part **21**, with a transversely extending, downwardly facing groove **31** located over and in facing relation with respect to the rearward groove **29**. Except for the grooves **28**, **29**, **30** and **31**, and the holes **17** and **18**, the barreled action **12** is dimensioned for conforming disposition in spaced relation within the groove **15** and stock opening **16**. That is, the barrel part **20** is received in spaced relation within the groove **15**, and the action part **21** depends in spaced relation within the stock opening **16**.

Interposed in the space between the barreled action **12** and stock **11**, completely spacing apart the former from the latter, is a bed or continuous layer of resilient bedding material, as at **32**. The bedding material, in accordance with the teachings of the instant invention is of a resilient characteristic, advantageously having adhesive properties and in adhesive engagement with substantially all of the facing surface areas of the stock **11** and barreled action **12**. For this purpose, a self-curing, semi-resilient adhesive such as that designated EC801 by Minnesota Mining Corporation has been found satisfactory. Said EC801 material

is a heavy liquid synthetic rubber compound which, upon the addition of an accelerator, chemically cures to a tough, rubber solid. In practice, a thickness of the layer or bed 32 of approximately $\frac{1}{10}$ inch is advantageous, but this thickness may vary.

In addition to the substantially constant-thickness resilient layer or bed 32, the material thereof is formed to extend integrally into the facing stock grooves 28 and 29 and barreled-action grooves 30 and 31, as at regions 33 and 34. These bed regions 33 and 34 are thus of increased thickness and provide effective shock-absorbing cushions by their resistance in shear.

The barreled action 12 may be of the type bolted to a stock, including forward and rearward headed studs or bolts 35 and 36 depending respectively into holes 17 and 18. Further, the headed studs 35 and 36 are surrounded by quantities or pads of resilient bedding material, as at 37 and 38, which material may substantially completely occupy respective holes 17 and 18 in bearing engagement with the under or inner sides of the heads of respective studs 35 and 36 to firmly and resiliently maintain the barreled action 12 in its bolted or tied relation with respect to the stock 11.

It will, therefore, now be understood that the barreled action 12 is effectively positively secured to the stock 11, while being isolated therefrom to cushion shock and the transmission of stresses therebetween.

In the embodiment shown in FIGURES 4 and 5, a stock is generally designated 11a, and may be essentially similar to the stock 11, including a longitudinally extending upwardly facing groove 15a, and a generally vertically extending through opening 16a passing downward from a rearward region of the groove 15a through the underside of the stock. The barreled action 12a of the embodiment of FIGURES 4 and 5 is similar to that of the first-described embodiment, including a barrel part 20a and an action part 21a. However, the barreled action 12a is of the recoil-lug type, including a lug 13 depending rigidly from the underside of barrel part 20a into spaced relation within an upwardly facing hole 14 in the stock 11. The stock is further formed with forward and rearward vertically extending through holes 17a and 18a, forwardly and rearwardly of the through stock opening 16a, the holes each passing downwardly from the groove or recess 15a through the underside of the stock, and there formed with enlarged regions 19 and 26, respectively. Headed fasteners or studs 35a and 36a are secured to the action part 21a and depend rigidly therefrom in spaced relation through respective holes 17a and 18a, terminating at their enlarged or headed ends within the enlarged hole regions 19 and 26.

The barreled action 12a is received in conforming spaced relation within the stock 11, being at all locations spaced therefrom with the groove 15a and opening 16a being lined with a bed or layer of resilient material 32a, in essentially the same manner as the layer 32 of the first-described embodiment. In addition, interposed between the interior surface of lug-receiving hole 14 and lug 13, to completely occupy the space therebetween, is an extension 27 of the layer 32a, advantageously integrally fabricated of the same resilient bedding material. Also, the holes 17a and 18a, and particularly the enlarged lower ends 19 and 26 are advantageously provided with pads or cushions 37a and 38a engaging the inner sides of the headed ends of fasteners 35a and 36a to effectively maintain firm securing between the barreled action 12a and stock 11a.

In the embodiment of FIGURE 4, the barreled action 12a is also effectively isolated from the stock 11a, to substantially reduce or cushion shock and minimize stress transmissions therebetween.

A further embodiment is shown in FIGURE 6, which is a cross-sectional view similar to FIGURES 3 and 5, a stock there being generally designated 11b and formed with a longitudinally extending upwardly facing groove 15b spacedly receiving a barreled action 12b, the space between the barreled action and facing surface of groove 15b being substantially fully occupied by a bed or layer 32b of resilient yieldable material, of the type disclosed hereinbefore.

In the embodiment of FIGURE 6, the barreled action 12b may include a barrel part 20b snugly surrounded by a reinforcing tube 40. The tube 40 serves to rigidify the barreled action 12b and the tube itself is securely adhesively seated in the bed 32b. This construction has been found to have remarkable accuracy under widely varying conditions of use.

From the foregoing, it is seen that the present invention provides a small-arms construction which fully accomplishes its intended objects and is well adapted to meet practical conditions of manufacture and use.

What is claimed is:

1. A small-arms construction comprising a stock, a barreled action associated with said stock, said barreled action comprising an action part and a barrel, a bed of resilient adhesive material interposed between said barreled action and said stock and in adhesive engagement therewith, and extending throughout the entire opposed contiguous areas between said barreled action and said stock thereby totally isolating said barreled action from said stock.

2. A small-arms construction according to claim 1, in combination with headed tie means extending from said barreled action spacedly through said stock, and pads of resilient bedding material interposed between said headed tie means and stock.

3. A small-arms construction according to claim 1, in combination with a recoil lug extending from said barreled action into spaced relation within said stock, and resilient bedding material surrounding said lug within said stock.

4. A small-arms construction according to claim 1, said barreled action and stock each being formed with transversely extending grooves with the grooves of said barreled action being in respective facing relation with the grooves of said stock, and resilient bedding material occupying said grooves to provide shock cushioning.

5. A small-arms construction according to claim 1, said bed of resilient material comprising a heavy liquid synthetic rubber compound which, upon the addition of an accelerator, chemically cures to a tough, rubber solid.

6. A small-arms construction according to claim 1, in combination with a reinforcing tube encircling the barrel part of said barreled action, said tube being bedded in said bed of resilient material.
